CLAIM

The ornamental design for a therapeutic travel and spa pillow, as shown and described.

DESCRIPTION

FIG. 1 is a top front perspective view of a therapeutic travel and spa pillow showing my design.

FIG. 2 is a bottom rear perspective view thereof;

FIG. 3 is an enlarged left elevational view thereof;

FIG. 4 is an enlarged right elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken line showing handles and straps is included for the purpose of illustrating environmental structure and forms no part of the claimed design.
